UNITED STATES PATENT OFFICE.

FRED A. WESCOTT, OF CORNING, NEW YORK.

DESIGN FOR A MOTOR-VEHICLE SIGNAL.

60,593.

Specification for Design.

Patented Mar. 7, 1922.

Application filed October 6, 1919. Serial No. 328,908. Term of patent 3½ years.

To all whom it may concern:

Be it known that I, FRED A. Wescott, a citizen of the United States, residing at Corning, in the county of Steuben and State of New York, have invented a new, original, and ornamental Design for a Motor-Vehicle Signal, of which the following is a specification, reference being had to the accompanying drawing, forming part thereof.

Figure 1 is a front elevational view of the invention, and

Figure 2 is an end elevational view of the same.

I claim:

The ornamental design for a motor vehicle signal as shown.

FRED A. WESCOTT.
